D. F. LINSLEY
CANISTER SHELL

2,461,555

Filed March 28, 1945

UNITED STATES PATENT OFFICE

2,461,555

CANISTER SHELL

Douglas F. Linsley, Greenwich, Conn.

Application March 28, 1945, Serial No. 585,376

9 Claims. (Cl. 102—42)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to ammunition.

An object of this invention is to provide an improved shell of the type which is filled with shot and commonly known as canister or shotgun type shells.

Another object of the invention is to provide improved means of causing the shot to be ejected from the canister shell casing.

A further object of the invention is to provide means for causing the canister shell casing to move at a speed less than the speed of the shot after leaving the gun, whereby the shot is separated from the casing.

Other objects and advantages of the invention will appear from the following description and claims.

A preferred embodiment of the invention has been illustrated in the drawings in which:

Figure 1 is a longitudinal sectional view of a shell embodying the invention.

Figure 2 is a longitudinal view of the projectile shown in Figure 1 as it leaves the gun barrel, showing the retarding vanes extended.

Figure 3 is a cross-sectional view taken along lines 3—3 of Figure 1.

Figure 4 is a fragmentary view of a portion of the shell as seen from the outside, and

Figure 5 is a detail perspective view of one of the retarding vanes.

As shown in the illustrations, there is a vane casing 2 and a hollow ball or shot casing 4. The shot casing 4 is located in the forward portion of the canister shell, and is filled with a number of balls 6, also known as shot. A front cover plate 8 serves to close the forward opening of shot casing 4. The casing 4 is narrower in cross-section at its rearward end 10 and increases in cross-section until it is widest at its forward end 12. A groove 14 near the forward end of the casing serves to slightly indent the casing and thus furnishes a support for cover plate 8.

The slot casing 4 has a flange 16 at its rearward end, and is joined to vane casing 2 by means of screws 18 threaded into holes 20 and 22 in the casings 2 and 4 respectively.

The vane casing 2 is provided with a central bore 24 which consists of an enlarged rearward portion 26 and a reduced forward portion 28. The reduced portion 28 should have a diameter small enough to keep out the balls 6. A number of vanes 30 are movably located in radial openings or

2

recesses 32 spaced around the casing 2 as shown. In the drawings, particularly Figure 3, a total of six vanes 30 has been indicated, each vane located in one of the six radial openings or recesses. One of the vanes 30 is shown in a perspective detail view in Figure 5. Each vane 30 has an L-shaped form. The horizontal leg 34 has a transverse hole 36 passing through it, and forms a right angle with the radial leg 38 of the vane 30. The leg 38 is provided with an elongated narrow aperture or slot 40 and two projections 42 extending parallel to the horizontal leg 34 as indicated, the projections 42 extending from the top end 44 of leg 38 downward toward but not reaching the bottom end 46 of the leg.

The casing 2 is also provided with a number of recesses 48 around its periphery, there being one recess 48 for each recess 32, all the recesses 48 being located in a plane parallel to the plane 20 of recesses 32 but spaced therefrom a short distance. Each recess 48 has an angular location equal to its corresponding recess 32 as shown. A radially elongated opening 50 wide enough to receive the leg 34 of vane 30 serves to connect each recess 32 with its corresponding recess 48. One vane 30 is inserted into each recess 32 with its horizontal leg 34 extending through opening 50 into recess 48.

Each screw 18 has an unthreaded slightly reduced extension 52 extending through the slot 40 of vane 30 so that the vane 30 is constrained to maximum radial motion along the distance defined by the length of slot 40. A coiled spring 54 is placed between the lower face of horizontal leg 34 of each vane 30 and the inner lower surface of each recess 32, the spring 54 being compressed when vanes 30 are inside the casing 2 and serving to urge the vanes 30 radially outward to the position shown in Figure 2. In the latter illustration 40 it is seen that the springs 54 have pushed each vane 30 radially outward so that the vanes extend partly outside the casing 2.

The shell is constructed so that the vanes 30 cannot be extended outwardly until the shell casing 2 has been fired out of the gun barrel. Thus, when the gun is fired, the springs 54 press the vanes 30 against the inner surface 3 of the gun barrel which surface prevents the vanes from extending beyond the casing 2 until the casing has 45 emerged from the barrel.

To facilitate handling the shell prior to insertion into the gun barrel, there is provided for each vane 30 a tie wire or cord 56 one end of which passes through the center of the shot casing 4 and is fastened to or looped through holes 55

55 in the center of the cover plate 8, and the other end of which passes through the bore 28 and into recess 48 through an aperture 58 connecting bore 24 with recess 48. The wire or cord 56 also passes through the hole 36 in vane 30 and is secured in the recess 48 by means of seals 60 which may be lead balls placed in each recess 48. Each seal 60 has a central hole 62 through which the wire 56 passes, and by squeezing the soft metal seal after the wire 56 has been inserted through it and the seal pressed down into the recess 48, the hole 62 is decreased in diameter and thus the wire 56 is tightly held within the constricted hole in the seal. The seals 60 may be formed in other shapes to facilitate squeezing them to grip the wire 56.

As the wire 56 passes from reduced bore 28 to bore 58, it passes over a portion 59 of the surface of the base of the enlarged portion 26 of the central bore 24. A cup shaped steel member 64 is pushed into the enlarged portion 26 of the bore, the fit being tight enough to hold the member 64 in the position indicated in Figure 1. The member 64 has a cutting edge 66, formed by beveling its forward end as shown. The cutting edge 66 is slightly spaced from the wires 56.

When the gun is fired, the pressure of the propellant gases forces the member 64 forward so its cutting edge cuts all the wires 56. Since the cut wires 56 no longer serve to hold the seal 60, the springs 54 then press the vanes 30 radially outward against the inner surface of the gun barrel. The vanes expand lightly against the barrel rifling and the result is to give the shell a spin. As soon as the shell leaves the barrel the vanes expand beyond the diameter of the shell as indicated in Figure 2, thus catching the air and acting as a retarding influence on the shell casing while it is in flight. The shell is given some added stability due to the spin derived from contact with the barrel rifling. The resulting centrifugal force assists the springs 54 in keeping the vanes extended.

Since the shell casing is retarded by the added resistance of the vanes, the balls 6, which fill the shot casing 4, continue their forward movement inasmuch as they are not subjected to the added retarding influence of the vanes. Thus the now unfastened cover plate 8 is pushed off by the balls and the balls 6 surge forward out of the shell.

The funnel shaped shot casing 4 will allow the exit of the balls in substantially a conical path whose longitudinal center line is parallel to that of the gun barrel, thereby causing widespread destruction at short range.

Once the cover plate 8 has been pushed off by the forward surge of the balls 6, the now open funnel shaped shell case acts in conjunction with the vanes as a retarding influence.

It should be noted that when the vanes expand lightly against the barrel, they will function equally well as a retarding influence whether or not the barrel is rifled, except that with a smooth barrel the shell will not be given a rotation. In other words, this canister type shell is adaptable for use in most types of cannons now in the field.

This shell is intended for use in guns using fixed semi-fixed, or separate loading ammunition. For purposes of illustration, Figure 1 shows the shell with a cartridge case 68 having a percussion primer 70 and containing a propelling charge 72. The shell casing 2 has an external groove 74 into which the forward end of the cartridge case is crimped if desired. For semi-fixed ammunition the crimping is omitted, and for separate loading the shell is used without the cartridge

case but with a separate propelling charge instead.

Although the invention has been described in specific terms, it is to be understood that changes may be made in the size, shape, arrangement and materials without departing from the spirit and scope of the invention as claimed herein.

I claim:

1. A canister shell comprising a casing having a forwardly open recess formed therein, a plurality of balls in said recess, a removable cover for closing said recess, at least one wire connecting said cover to said casing, a plurality of radial apertures in the rearward portion of said casing, vanes movably located in said apertures, spring actuated means in said apertures for extending said vanes partly outside said casing as said casing is fired from a gun barrel, detent means for holding said vanes retracted inside said apertures, and means actuated by the pressure of propellant gases on firing said shell for cutting said wire and for releasing said detent means.

2. The construction of claim 1 wherein said recess is frusto-conical in shape, its larger sized end being located at the forward end of said casing.

3. The construction of claim 2 wherein said vanes are L-shaped, having their horizontal legs parallel to the axis of the shell and their vertical legs extending radially outward, said vertical legs having an elongated longitudinal aperture formed therein for defining the limits of radial movement of said vanes, studs projecting from said casing into each of said apertures for limiting the radial movement of said vanes.

4. A canister shell comprising a casing having a forwardly-opening shot chamber therein, a plurality of shot in said chamber, first means carried by said casing and projectable laterally outwardly therefrom from a first, to a second position, second means urging said first means into said second position, wire means restraining said first means in said first position, and cutting means actuated in response to firing of said shell for severing said wire means whereby said second means acts to project said first means into said second position to retard the flight of said casing only.

5. In a shell for guns, a casing forming a forwardly-opening chamber, a plurality of shot in said chamber, first means comprising laterally movable vane and rifling-engaging elements carried by said casing and movable from a position within the confines of said casing to a position projecting outwardly of said casing, second means resiliently urging said first means into said outwardly projecting position, third means releasably maintaining said first means in said casing engaging position, and cutting means carried by said casing and operated by and in response to firing of said shell to sever said third means to thereby permit said second means to move said first means into position engaging the bore of said gun during passage through the barrel thereof and into outwardly projecting position upon emergence of said shell from said gun.

6. A canister shell comprising a casing forming a forwardly-opening chamber, a plurality of shot in said casing, cover means removably secured over said opening, a plurality of vanes carried by said casing means yieldingly urging said vanes from a first position within the confines of said casing radially to a second position outwardly of said casing, common means normally holding said vanes in first position and said cover means over said opening, and severing means operated by fir-

ing of said shell to sever said common means and release said vanes for movement to said second position.

7. A canister shell comprising a casing having a forwardly open recess therein, a plurality of bullets in said recess, a cover removably positioned over said recess to close the same, vanes carried by said casing and radially extensible therefrom to increase the air resistance of said shell, spring means urging said vanes into extended position, shearable means holding said cover in position and said vanes in retracted position, knife means slidably mounted in the casing and movable into engagement with said shearable means responsive to firing of said shell to shear said shearable means.

8. A canister shell comprising a casing having a forwardly-open recess therein, a plurality of bullets in said recess, a cover removably extending over, and closing said recess, a plurality of vanes in said casing and extensible laterally therefrom for increasing the wind resistance of said casing in flight, resilient means urging said vanes into extended position, severable means normally holding said cover in position over said recess, and said vanes in retracted position, and pressure-actuated severing means operated by firing of said shell to sever said severable means and thereby release said vanes and cover.

9. A canister shell comprising a first casing having a forwardly-opening chamber, a plurality of bullets in said chamber, a cover closing the forward opening in said chamber, a second cylindrical casing secured to the base of said first casing and having a series of equally spaced radial

apertures opening through the periphery thereof, a vane positioned in each aperture, spring means urging said vanes radially outward of said apertures, means carried by said casing limiting said radially outward movement, a series of equally spaced radial openings in said casing, each said opening being adjacent a respective aperture, each said vane having a portion extending into a respective opening, a deformable element in each opening radially outward of said portions, wire means connecting said cover with each said element to retain said cover in position and said vanes in retracted position, said wire means passing through a passageway between said casings, and knife means in said second casing and movable into engagement with said wire means to sever the same, said knife means being moved by and in response to pressure engendered in firing of said shell.
